UNITED STATES PATENT OFFICE.

DUSTIN F. MELLEN, OF WENTWORTH, NEW HAMPSHIRE.

MACHINE FOR SAWING CLAPBOARDS, &c.

Specification of Letters Patent No. 11,568, dated August 22, 1854.

To all whom it may concern:

Be it known that I, D. F. MELLEN, of Wentworth, in the county of Grafton and State of New Hampshire, have invented 5 certain new and useful Improvements in Machines for Sawing Clapboards, of which the following is a full, clear, and exact description, reference being had to the accompanying drawings, making part of this 10 specification.

In machines for sawing clapboards as heretofore constructed a single stationary saw has been employed, the log being moved longitudinally above it and lowered as the 15 successive layers of clapboards were taken off.

The object of my improvements is to accelerate the operation and increase the product of machines of this kind, and my invention 20 consists firstly in the arrangement of two saws in swinging frames which are allowed to vibrate to and from each other to accommodate the distance between them to the varying diameters of the logs from 25 which the clapboards are to be cut.

After each cut of the saw it becomes necessary that the log be revolved or fed an amount equal to the thickness of another clapboard; this feed when once adjusted 30 should remain invariable as otherwise the thickness of the clapboards will vary. If the feeding pawl be caused to strike against a stationary dog the feed may be greater at one time than at another should the momentum of the carriage vary. If the motion of the feeding pawl be limited by a 35 fixed stop unless the motion of the carriage cease at the exact instant when the pawl is brought down upon its stop, great strain if 40 not the rupture of some of the parts, will be the consequence. To remove this difficulty is the object of my third improvement which consists in causing the feeding pawl to strike against a rigid stop and in combination therewith in actuating the pawl by a spring dog that the latter may yield even 45 though the carriage continue to progress after the feeding pawl has been brought down upon its stop, by which combination 50 great regularity of feed and uniformity of thickness in the clapboards is obtained.

My machine is adapted to operate with two saws as already mentioned, both of them making a cut at each motion of the 55 carriage; it may be desired however with

refractory lumber or where there is a deficiency of power, which latter often occurs in seasons when the streams are low, to operate the saws singly, each making its cut as the carriage takes out or in; to accomplish this 60 is the object of my fourth improvement, which consists in a peculiar method of raising and lowering the saws so as to bring them alternately into operation, as will be hereafter fully explained. 65

To enable others skilled in the art to make and use my invention I will proceed to describe the manner in which I have carried it out.

In the accompanying drawings Figure 1 70 is a perspective view of a machine with my improvements attached. Fig. 2 is a plan of the same. Fig. 3 a longitudinal section upon the line A A of Fig. 2. Figs. 4, 5, 6, 7, 8, 9, 10 and 11 are details which will be referred 75 to hereafter.

The general features of the machine will first be described and then the improvements which I have added thereto.

C is the frame work of the machine, D 80 the carriage in which the log is dogged, from which the clap-boards are to be cut. This carriage runs upon ways E and is driven back and forth with an equable motion in the following manner.

F is a rack bar which is hinged to the rear of the carriage at a and engages with the cog wheel b upon the transverse shaft c; this shaft also carries another cog wheel G which engages with the gear d upon the 90 shaft f. This latter shaft is driven alternately in one direction and the other for the purpose of bringing in and carrying out the carriage, in the following manner.

H is a set of cone pulleys loose upon the 95 shaft f which are driven in one direction by a band from a corresponding set of pulleys K upon the main driving shaft M. I is another set of pulleys also loose upon the shaft f and which are driven in a contrary 100 direction by a crossed band from the pulleys L also on the main shaft. The pulleys H and I are alternately made to drive the shaft f in one direction and the other by the clutch O which runs with a spline upon 105 the shaft and which is operated by the carriage as follows.

P is the shipper rod which carries adjustable dogs g, g'; these dogs are alternately struck by the shipper h upon the carriage, 110

as the latter arrives at the opposite ends of its traverse, and thus the rod P is slid in one direction and the other, by which motion is given to the vertical lever Q , which 5 is jointed to the rod P and pivoted at i . This lever is connected by the rod R to the bent lever S, S' , Fig. 9 pivoted at k , by which means the bar T and clutch O are moved, the arm U upon the former guiding the latter in the customary manner.

10 By moving the clutch O the shaft f is caused to revolve alternately in one direction and the other, and the carriage is taken out and in—the springs x in advance 15 of the dogs g, g' receive the blow from the approaching carriage and prevent it from injuring by its momentum the parts connected with the shipper rod.

The saws are arranged in the following 20 manner V, V' , are the frames which vibrate around the main shaft M and carry the saw shafts W, W' at their outer extremities, these shafts are driven by bands A', A'' , from the pulleys B, B' upon the main driving shaft.

25 The position of the saws X, X' with respect to each other and with respect to the log is determined in the following manner.

l is a small shaft running transversely 30 across the upper frame V and carrying two pulleys m , and a ratchet wheel n . This shaft is turned by a key upon one of its ends which is made square for the purpose, or in any other suitable manner, and is retained in position by a pawl O .

35 p are chains which pass around and are secured to the pulleys m , their other ends being attached to the lower saw frame V' . This distance between the saw frames is adjusted by winding up or letting go the chains p . The two frames are raised and lowered together to accommodate their position to that of the log in the following manner. q are chains one end of each of 40 which is attached to the upper frame V at r ; these chains pass over the guide rollers s , down through the frame work at t , and are attached at their other ends to pulleys u upon a shaft a' which runs in bent levers b' 45 pivoted at the point e' upon opposite sides of the frame work. The bent lever b' is connected at the point d' with the rod f' for a purpose to be hereafter explained. The shaft a' is furnished with a ratchet 50 wheel and pawl similar to those upon the shaft l for the purpose of raising and lowering the saw frames.

55 Where it is desired to operate but one of the saws at a time one cutting as the log advances, and the other as it returns the following device is made use of to bring them alternately into operation.

60 h' is a bolt or catch Figs. 2, 3, 7 and 8 which is hinged to the frame of the machine and enters one or other of two notches i' in

the adjustable dogs k' which are secured to the rod f' .

e' is a spring which bears the catch h' outward and forces it to enter the notches i' at certain intervals.

70 l' is a rod lying immediately over the rod f' , and furnished with a wedge formed piece m' , the object of which is to press back the catch h' out of the notches in the dogs k' , and thus permit the rod f' to be moved longitudinally.

75 n', o' , are adjustable dogs upon the rods f', l' , these dogs are operated upon by the shipper p' attached to the carriage. The dogs n' are set in advance of those upon the shaft f' , and as the carriage advances the shipper p' moves the rod l' longitudinally until the piece m' comes in contact with the catch h' and presses it out of the notches i' . The shipper p' then strikes the dog O' which 80 slides the rod f' into a position which enables the catch h' to enter the other notch i' the piece m' having in the meantime passed by to allow the catch to spring into the notch. The parts remain in this position until on the return of the carriage the shipper p' is made to operate upon the other set of dogs n', o' Fig. 3 by which means the 85 rod f' is returned to its former position and held there by the catch h' which enters the other notch i' Figs. 2 and 8 as before. The rod f' being connected as before described with the bent lever b' , the latter receives an intermittent vibratory motion around its fulcrum C' , and the saw frames through the 90 connections already described are thus raised and lowered causing the saws alternately to operate upon the log. This portion of the apparatus is only to be made use of where unusually refractory lumber or a 95 deficiency of power renders it necessary to employ but one of the saws at a time.

100 After each successive cut the log is fed in the following manner. t' is a spur center, upon which the log is centered, and which carries at its other end the cog wheel u' which engages with the cog wheel v' ; this wheel again engages with the pinion w' made fast to the bevel wheel x' , which gears with the bevel wheel y' ; upon the shaft a'' of this wheel is secured the ratchet wheel z ; loose upon this same shaft vibrates the pawl lever b'' of the form represented in Figs. 4, 5, and 6, this lever carries a pawl c'' 105 which engages with the teeth of the ratchet wheel z ; d'' is a set screw which limits the motion of the lever b'' the latter being borne away from the set screw by the spring e'' ; these parts are all attached to the carriage.

110 Motion is given to the lever b'' in the following manner: f'' is a rod which slides freely in the sockets g'' , and has attached to it the adjustable dog h'' , against which bears the spring i'' which tends constantly 115 to 120 125 130 135 140 145 150 155 160 165 170 175 180 185 190 195 200 205 210 215 220 225 230 235 240 245 250 255 260 265 270 275 280 285 290 295 300 305 310 315 320 325 to keep the dog in contact with one of the sockets g'' , and to hold the rod f'' in the position seen in Figs. 1 and 2.

As the carriage advances the pawl lever 5 b'' strikes against the rod f'' and is forced down upon the stop d'' communicating through its pawl c'' and the intermediate gearing a determinate and unvarying feed to the log. Should the momentum of the 10 carriage drive it still farther after the feed has been effected, or should the parts which arrest its motion not be in proper adjustment the spring i'' will yield allowing the lever b'' to press back the rod f'' and thus 15 no breakage of the parts will occur. Were the lever b'' permitted to strike against a stationary rigid stop and the motion of the carriage continued after the lever was down upon this stop, the breakage of the parts 20 would inevitably result.

Operation: The log being centered in the carriage as seen in Figs. 2 and 3. The saws are adjusted to the proper distance apart by turning the shaft l and winding up or letting out the chain p . The position of the 25 two saws with regard to the log is then adjusted, by means of the chain q and the shaft a' , the saws being raised or lowered until they are at an equal distance above 30 and below the center of the log; the log is then allowed to traverse, being driven in one direction or the other as before explained, by the wheel b upon the shaft c , which engages with the rack bar F attached 35 to the carriage, each saw making a cut upon opposite sides of the log. As soon as the log has passed beyond the saws, the lever b'' (Figs. 2, 4, 5, 6) strikes against the end of the rod f'' and the log is revolved the thickness of another clapboard, through the connections already explained, the spring i'' yielding should the carriage continue to advance after the lever b'' is down upon its stop d'' . The next instant the shipper h 40 upon the carriage strikes the dog g or its accompanying spring upon the shipper rod rod P , by which means the clutch O is moved, and the motion of the carriage is reversed. When the log has again passed 45 from under the operation of the saws, the lower end n'' of the lever b'' strikes against the spring rod m'' , the operation of which is similar to that of f'' and the log is again fed round as before. An entire ring of 50 clapboards having been cut from the log, the saws are made to approach each other an amount equal to double the width of the clapboard, by winding up the chains p upon the pulleys m , the position of the saws being 55 again adjusted with respect to the log, by 60 means of the chain q and pulley u , and the works proceeds as before. It is evident

that there are other methods by which the saws may be adjusted, with respect to each other and the log, which are, the entire 65 equivalent of the chains and pulleys above referred to.

When from any of the causes above referred to, such as unusually refractory lumber or a deficiency of power, it may be found 70 necessary to allow only one of the saws to operate at the same time the apparatus for alternately raising and lowering them already described is brought into use, the upper saw being made to operate, while the log 75 is moving in one direction, and the lower saw while it moves in the opposite direction. It will be perceived that after the saws are adjusted to the particular size of 80 the log to be operated upon, all the motions of this machine are automatic, whether the saws be made to operate alternately, or together; in the latter case, two clapboards are cut each time the carriage moves either forward or backward while the peculiar 85 manner in which the cutters which dress the surface of the log are arranged and operated enable the machine to be operated at a speed far exceeding that heretofore attained upon machines of this class. 90

I do not claim two saws operating simultaneously upon opposite sides of the same piece of lumber; but

What I do claim as my invention and desire to secure by Letters Patent is, 95

1. The arrangement of devices substantially as described, by which the distance between the saws is varied to meet the varying thickness of the logs to be sawed, and the saws, when so adjusted, are elevated and 100 depressed together as required.

2. I claim the method substantially as herein described of feeding the log between each successive cut of the saws, that is to say causing the feeding pawl, or the lever which 105 carries it, to strike against a fixed stop, in combination with the yielding dog h'' arranged and operating as set forth.

3. I claim the method substantially as herein set forth, of raising and lowering the 110 saws, when it is desired not to use them at the same time, but alternately during the forward and backward motion of the log, the same being effected by the combination of the unlocking, shifting and locking apparatus m' , h' , k , k' , in combination with the lever b' and chains q , the whole operating in the manner substantially as herein 115 set forth.

DUSTIN F. MELLEN.
